US0D1042134S

(12) **United States Design Patent** (10) **Patent No.:** **US D1,042,134 S**
(45) **Date of Patent:** **** Sep. 17, 2024**

(54) **CONTAINER**

(71) Applicant: **S. C. Johnson & Son, Inc.**, Racine, WI (US)

(72) Inventors: **Brian T. Davis**, Burlington, WI (US); **Julianna Miller**, Boston, MA (US); **Miguel M. Bual**, Lisbon (PT)

(73) Assignee: **S. C. JOHNSON & SON, INC.**, Racine, WI (US)

(**) Term: **15 Years**

(21) Appl. No.: **29/706,733**

(22) Filed: **Sep. 23, 2019**

(51) LOC (14) Cl. **09-03**

(52) U.S. Cl.

USPC **D9/500**; D9/558

(58) **Field of Classification Search**

USPC D9/500, 516, 503, 549, 558, 574, 767,

D9/772, 499, 529, 504, 764; D24/224

CPC B65D 2543/00092; B65D 1/165; B65D

1/0246; B65D 1/02

See application file for complete search history.

CLAIM

The ornamental design for a container, as shown and described.

DESCRIPTION

FIG. 1 is an isometric view of a top, front, and left side of an ornamental design for a container;

FIG. 2 is a front elevational view of the container of FIG. 1; FIG. 3 is a rear elevational view of the container of FIG. 1; FIG. 4 is a left side elevational view of the container of FIG. 1;

FIG. 5 is a right side elevational view of the container of FIG. 1;

FIG. 6 is a top plan view of the container of FIG. 1; and, FIG. 7 is a bottom plan view of the container of FIG. 1.

The broken lines are included for the purpose of illustrating portions that form no part of the claimed design. The dash-dot-dash lines are included for the purpose of illustrating boundary lines and form no part of the claimed design.

1 Claim, 4 Drawing Sheets
